CLAIM

The ornamental design for a tail lamp signature for a vehicle, as shown and described.

DESCRIPTION

FIG. 1 is a front left perspective view of a tail lamp signature for a vehicle.

FIG. 2 is a front view of the tail lamp signature.

FIG. 3 is a left side view of the tail lamp signature.

In FIGS. 1-3, the elements of the tail lamp signature are surrounded by broken lines, which form unclaimed boundaries of the design elements. The rest of the tail lamp is shown in de-emphasized and half-tone portions to illustrate environmental structure.

FIG. 4 is a front view of the tail lamp signature shown in FIGS. 1-3, but with the tail lamp signature located on the left side of a vehicle, and the rest of the vehicle shown in de-emphasized and half-tone portions to illustrate environmental structure. These portions form no part of the claimed design. More particularly, in FIG. 4, the elements of the tail lamp signature are bounded by broken lines, which form unclaimed boundaries. As in FIGS. 1-3, the rest of the tail lamp and the rest of the vehicle form no part of the claimed design, but are instead included to show environmental aspects thereof; and,

FIG. 5 shows an alternative embodiment, but with the tail lamp signature as shown in FIG. 4 combined with a mirror image tail lamp signature located on the right side of the same vehicle.

1 Claim, 5 Drawing Sheets
